CHEMICAL PROCESS

Herbert G. M. Fischer, Westfield, N. J., assignor to
 Standard Oil Development Company, a corpora-
 tion of Delaware

Application May 31, 1941, Serial No. 395,920

7 Claims. (Cl. 196—55)

1

The present invention relates to the art of treating hydrocarbon oils to obtain desired products, and more particularly it relates to the thermal treatment of heavy residuums obtained from crude petroleum oil by topping the latter to remove constituents boiling up to about 700°—850° F.

In processing a crude petroleum oil, the modern refiner must deal with the crude material in a manner to provide maximum quantities of desired products, and from time to time the commercial demand for certain petroleum products may vary widely. For example, in the northern part of the United States during the winter months the demand for domestic heating oil may greatly exceed the demand for any other particular product readily obtainable from crude petroleum oil by simple distillation and, as a result, it is often necessary during the winter season to process topped crudes to recover additional quantities of hydrocarbon oils which are suitable for use as a domestic heating fuel. On the other hand, during the summer months the commercial demand for gasoline and motor fuels may be such as to require an entirely different treatment of petroleum crude oils in order to obtain the maximum production quantities of gasoline. Ordinarily when a crude oil is received in a modern refinery it is the practice to subject it to a simple distillation, and in this operation, together with normally gaseous hydrocarbons, gasoline, naphtha and gas oil are obtained. The residue, often called a reduced crude, is then processed to obtain valuable constituents, such as lubricating oil, paraffin wax, asphalt, and the like.

When, however, the commercial demand is such that increased quantities of gasoline are desirable, the reduced crude may be subjected to a thermal treatment whereby a quantity of hydrocarbons boiling within the gas oil range are obtained, which gas oil may serve as a charging stock to a thermal or catalytic cracking unit for producing motor fuel of high octane rating. The thermal treatment referred to is usually a coking operation in which the reduced crude is converted to vaporizable hydrocarbons and a solid coke.

The coking operation, as ordinarily practiced in a modern refinery, entails a number of practical operating difficulties and disadvantages. Probably the most troublesome aspect of a coking operation is the removal of the coke from the coking zone. The coking operation is generally performed by heating the reduced crude to a temperature within the range of from 800°—1000° F., usually in a coil, and then discharging the

heated oil into a chamber where the oil is maintained at the temperatures indicated and under atmospheric or superatmospheric pressure for a sufficient period of time to effect the desired conversion. As the process of coking proceeds in the chamber, the coke formed in the process accumulates progressively until finally a time is reached when the coking operation with respect to a particular chamber must be discontinued in order to remove the coke. The decoking is a time-consuming and laborious operation since the coke forms a strong, tough mass which to completely remove, as stated, involves a great deal of labor.

Usually after a coking chamber has been taken off the onstream operation, it is first permitted to cool, whereupon the operators remove the coke.

The coke removal in the ordinary intermittent coking process is an operation which consumes considerable time and labor and, consequently, any method which will eliminate a substantial portion of the time and cost necessary to decoke a chamber would effect a material advantage.

The main object of the present invention is to carry out the coking of heavy petroleum oils continuously by forming the coke in such a manner that it is highly frangible, relatively soft, and adapted to be continuously removed from the coking zone.

A more specific object of my invention is to carry out a coking operation in the presence of added cellulose linters, threads, sawdust, wood flour or other cellulosic material in divided form, under conditions such that the charcoal resulting from the added cellulosic material intermixes with the formed coke and greatly reduces the tensile strength of the latter so that it may be easily removed from the coking zone.

Other and further objects of my invention will appear from the ensuing more detailed description of my present invention.

The present invention will be best understood by reference to the accompanying drawing which shows diagrammatically a form and arrangement of apparatus elements in which my process may be carried into practical effect. I shall describe the process in terms of the coking of a specific reduced crude, but it is to be clearly understood that the specific example I have chosen is purely illustrative and does not constitute a limitation of my invention.

Referring in detail to the drawing, a reduced East Texas crude petroleum oil having an A. P. I. gravity of 18° is introduced into the system 55 through line 1. Sawdust of the ordinary com-

3

mercial grade is withdrawn from hopper 14 through star feeder 16 and conduit 17 and discharged into the oil in line 1 and thereafter a slurry of sawdust and oil is discharged by pump 3 into a coil 4 dispersed in a suitable furnace setting 5. In coil 4 the oil is heated to a temperature of from about 800° F. to 1100° F., and during the heating operation the sawdust is at least partially converted to charcoal. The heated oil is withdrawn from the coil through line 9 and discharged into the top of coking drum 25 as shown. In order to assist in the vaporization of the oil, steam at a temperature within the range of from about 825° F. to 1100° F. is discharged into the upper part of drum 25 through line 28. Instead of introducing the sawdust into the liquid oil in line 1, the sawdust may be introduced into the vapors in line 9, employing for the mixing of the oil vapors into the sawdust any suitable device, such as an injection means. This may be accomplished by means of the by-pass 51. Valves 52 and 53 are arranged respectively in lines 17 and 51 to control the flow of the finely divided solid either to the heating coil or to line 9. In either event the amount of sawdust mixed with the oil may be from 1% to 10% by weight of sawdust and 90% to 99% oil.

The oil, ordinarily vaporized at least in part containing sawdust and/or charcoal in line 9, however introduced therein, is then discharged 30 as indicated into the top of coking drum 25. The oil passes downwardly through the drum 25 and during this passage it is converted to vaporizable hydrocarbons and non-vaporizable hydrocarbons. A heavy oil or tar is formed in drum 25 under the 35 conditions stated, particularly in the upper section of the drum represented by A. The tarry material thereafter continues its downwardly progress through the drum and the conversion continues.

The heavy oil and the tar formed in the region generally indicated by A are converted to a frangible coke in the region generally indicated by B. This coke contains the charcoal resulting from the carbonization of the sawdust, and it is this charcoal which forms a weak link in the structure of the coke so that the same may be readily broken into lumps and thus readily removed from the coking drum. If desired, grinding or crushing means 29 may be positioned in the lower portion of drum 25 to disintegrate and reduce the coke into readily removable lumps. Additional steam, say at a temperature of 825° F. to 1100° F., may be discharged into the drum through line 30 in order to purge the coke of volatile constituents.

The coke is withdrawn from the drum through a star feeder 31 and conduit 32. Since the coke issuing from the drum 25 is at an elevated temperature, it is desirable to force the withdrawn coke through a suitable cooling means 35 to reduce its temperature. This cooling means may consist of water, or any other cooling fluid which may be circulated in a jacket surrounding conduit 32, or which may be sprayed directly on the hot coke. The cooled coke is then discharged into a receiving bin 40 at a temperature such that it will not ignite upon exposure to the air. Ordinarily a safe temperature would be one below 300° F. to 325° F.

The vapors formed in the coking drum 25 are withdrawn overhead through line 41 and delivered to a fractionating column 42. Ordinarily the coking operation results in the production of 5-25% of gasoline and normally gaseous hydro-

carbons, together with light and heavy naphtha, and light and heavy gas oil. These fractions may be recovered in any known manner and usually a heavy fraction is recycled to the line 1 for further treatment in the process. A light fraction may be taken off from the top of column 42 by line 43 and a heavy fraction by line 50.

In order to point out the advantages of my present invention I may direct attention to a run which I made on an East Texas reduced crude having an A. P. I. gravity of 18°, under the conditions hereinbefore specified, in which I employed 2% by weight of sawdust and found that 8% by weight of a friable, porous coke, based on the original feed, was formed. This coke was of such form and condition that it could be easily removed from a coking drum. I made a similar run with the same feed stock but omitted the sawdust, and I found that I obtained 15% by weight of coke and that the said coke was dense and hard and was difficult to remove from a coking drum. Therefore, there are two advantages in my present process, as follows: First, the amount of coke produced from a given stock is less and this means, of course, that more vaporizable hydrocarbons are produced, which is a known desideratum; and, second, the coke which I produced was easily crushable and porous in the case where I employed sawdust, while the reverse was true when sawdust was omitted.

To review briefly, the present invention relates to a continuous coking operation carried out in the presence of a friable cellulosic material, such as sawdust, the sawdust serving to form an adsorbent charcoal during the heating, which charcoal is intermixed with the formed coke and renders the latter readily disintegrable or crushable so that it may be substantially continuously removed from the coking zone. A relatively small amount of sawdust present in the oil during coking is sufficient to accomplish the desired result. I have found, for instance, that 2% by weight of sawdust based on the oil fed is sufficient to produce a soft coke. The sawdust which I may add may be either green wood sawdust or dry sawdust. From a commercial standpoint, as well as from a technical standpoint, sawdust is a very desirable material since it is relatively inexpensive, constituting to a large extent a waste product from saw-mills, and the like. I may of course use divided cellulosic material, such as in the form of wood flour, wood chips, wood meal, cotton linters, cottonseed hulls, etc.

The operation previously described is carried out under normal atmospheric pressure, but it is to be understood that my process is broad enough to be carried out under superatmospheric pressure; for instance, pressures as high as 100-500 lbs./square inch in the coking zone. The amount of steam, if used, may be from 5-10 mol per cent and this quantity is fed into the drum 25 through lines 28 and 30 as indicated. A temperature of about 1100° F. in coking drum 25 gives excellent results.

Many modifications of my invention will be apparent to those who are familiar with this particular art.

What I claim is:

1. A continuous method of producing coke which is frangible and easily disintegrated, comprising the coil preheating of a heavy petroleum oil to coking temperature but without substantial coke formation, commingling a cellulosic material with the preheated oil, passing the commingled preheated oil and cellulosic material into

a zone wherein coke is formed, continuously disintegrating the coke adjacent a point of withdrawal from said zone, and continuously removing coke therefrom.

2. A continuous method of producing coke which is frangible and easily disintegrated, comprising the coil preheating of a heavy petroleum oil to coking temperature, but without substantial coke formation, commingling wood sawdust with the oil while the oil is being preheated whereby the wood sawdust is at least partially converted into charcoal, passing the commingled preheated oil and partially converted wood sawdust into a zone wherein coke is formed from the oil in intimate admixture with the charcoal, continuously disintegrating the admixed coke and charcoal adjacent a point of withdrawal from said zone, and continuously removing the admixed coke and charcoal therefrom.

3. A continuous method for converting thermally a relatively heavy petroleum oil residual into vaporizable hydrocarbons containing substantial quantities of gas oil and coke-forming constituents, which process is characterized by the feature that the coke produced is frangible and readily crushable, which comprises mixing

1% to 10% of cellulosic material with a reduced crude petroleum oil and heating the mixture to a temperature within the range of from about 800° F. to 1100° F., thereafter discharging the oil and cellulosic material into a coking zone, permitting the oil and cellulosic material to remain in contact with each other at conversion temperatures in the coking zone for a sufficient period of time to convert the oil into gas, gasoline and gas oil and to carbonize the cellulosic material, recovering gas oil, gasoline and gas from the coking zone, and separately and continuously recovering the coke formed, together with the charcoal formed, intimately mixed in the form of a frangible, readily crushable, non-adherent mass.

4. The process set forth in claim 3 in which the cellulosic material is sawdust.

5. The process set forth in claim 3 in which the cellulosic material is wood flour.

6. The method set forth in claim 3 in which the coke and charcoal mass are ground and then recovered from the coking zone.

7. The process set forth in claim 3 in which the cellulosic material is sawdust and in which the amount of sawdust is 2% by weight of the oil.

HERBERT G. M. FISCHER.
